R. J. Dearborn

Patented Dec. 18, 1928.

UNITED STATES PATENT OFFICE.

HARRISON O. PRESTON, OF PORT ARTHUR, TEXAS, ASSIGNOR, BY MESNE ASSIGNMENTS, TO THE TEXAS COMPANY, OF NEW YORK, N. Y., A CORPORATION OF DELAWARE.

CONTAINER FOR LUBRICANTS.

Application filed July 31, 1924. Serial No. 729,241.

This invention relates to improvements in dispensing apparatus for plastic or semi-plastic materials and more particularly has reference to apparatus for dispensing grease, 5 solid or semi-solid oils and lubricants in general.

The object of my invention is to provide a container for lubricants which may be inserted bodily into a lubricant ejector. A 10 further object is to provide a container capable of being inserted full length into an ejector and thereafter permitting the lubricant to be retained in the ejector while removing the container.

15 Further advantages of my invention will become apparent upon referring to the following description and drawings:

Figure 1 is a side elevation, partly in section, of a grease filled container.

20 Figure 2 is a sectional elevation of a grease gun showing the cartridge in position in the grease gun barrel.

Figure 3 is a sectional elevation showing the method of withdrawing the container 25 to leave the lubricant in the grease gun barrel.

Figure 4 is a sectional elevation of a grease gun showing the lubricant partly ejected.

30 In Figure 1, 1 is a grease gun cartridge shell having a false bottom consisting of a disk 2 which just fits the interior of the shell. The disk 2 is prevented from moving in an outward direction by an annular groove 3 but it is free to move in an inward direction the full length of the shell. An annular flange 4 is formed at the base of the cartridge shell and serves as a grip in removing the shell from the grease gun 35 barrel. A cap 5 is provided for the top of the cartridge to prevent dirt or other foreign materials from contaminating the lubricant.

40 Figures 2 and 3 indicate the method of transferring the contents of the cartridge shell 1 to a grease gun barrel. The grease gun has a barrel 6, having a constricted portion and outlet 7. It also has a piston 8 and a piston rod and handle 9, which passes through the threaded top 10 and is guided thereby. In 45 transferring the lubricant from the cartridge shell 1 to the grease gun barrel 6, the cartridge cap 5 is removed from the cartridge and the latter is then inserted practically full length in the open barrel. A small tool,

such as the screw driver 11, is now placed 55 under the slid able disk 2, while the cartridge shell is grasped by the flange 4 and pulled downwardly, leaving the contents in the grease gun.

In discharging a grease gun of the usual 60 type, a small amount of lubricant will remain in the constricted portion or the outlet. The ordinary type of grease gun cartridge is designed to be placed at the top of the grease gun barrel and its lubricant content 65 is forced into the barrel by moving a false bottom similar to that shown in the present invention. In carrying out this operation a pocket of air is formed between the incoming lubricant and the lubricant remaining 70 at the outlet of the grease gun. As it escapes this air either forces out the lubricant remaining in the outlet or causes a certain amount of it to ooze out of the top of the grease gun, in either case the hands of 75 the user are likely to become soiled and lubricant wasted.

My invention avoids these difficulties by 80 allowing the insertion of the cartridge full length into the grease gun barrel before attempting to remove the contents. Thus while the cartridge is being inserted the air contained in the grease gun barrel will have 85 an opportunity to escape between the sides of the cartridge and the grease gun barrel, because these parts do not fit in air tight 90 relation. The cartridge shell may now be removed from the grease gun barrel in the manner previously described during which operation the mass of lubricant being transferred from the cartridge remains in substantially its original position in the grease gun.

What I claim is:

A grease gun cartridge comprising a shell 95 having a cylindrical body portion adapted to be inserted substantially full length into a grease gun, an external annular flange at the lower end of the shell for preventing the further insertion of the same into said 100 grease gun, a disk movable within the shell and an internal annular constriction at the lower end thereof for preventing movement of said disk in an outward direction.

In witness whereof I have hereunto set my 105 hand this 23rd day of July, 1924.

HARRISON O. PRESTON.
